UNITED STATES PATENT OFFICE

CHARLES N. MONTEITH AND FRANK R. CANNEY, OF SEATTLE, WASHINGTON, ASSIGNEES
TO BOEING AIRPLANE COMPANY, OF SEATTLE, WASHINGTON, A CORPORATION OF
WASHINGTON

DESIGN FOR A TRANSPORT AIRPLANE

Application filed June 7, 1932. Serial No. 44,012. Term of patent 3½ years.

To all whom it may concern:

Be it known that we, CHARLES N. MONTEITH and FRANK R. CANNEY, citizens of the United States, residing at Seattle, in the county of King and State of Washington, have invented a new, original, and ornamental Design for Transport Airplanes, of which the following is a specification, reference being had to the accompanying drawings, forming part thereof.

Figure 1 is a plan view of the airplane, showing our new design.

Figure 2 is a front elevation of the same in flight.

Figure 3 is a side elevation of the airplane in flight.

We claim:

The ornamental design for a transport airplane, as shown.

Signed at Seattle, King County, Washington, this 28th day of May, 1932.

CHARLES N. MONTEITH.

FRANK R. CANNEY.
